BUILDING BLOCK

Alfred H. Stamm and Harry S. Barton,
Peoria, Ill.

Application January 18, 1939, Serial No. 251,461

9 Claims. (Cl. 72—41)

This invention relates to improvements in building blocks adapted for the construction of the walls of buildings.

The main object of the invention is to so construct a building block that water which may chance to enter the inside of said block due to leaks in a constructed wall will be guided to but one face or side thereof, or that face or side of said block known as the outer face as distinguished from the inner side, or the plaster-bearing face or side thereof.

In addition to this our building block includes certain structural features believed to be new and which will be made known with the aid of the appended drawing forming part hereof wherein—

Figure 1 shows in perspective a building block according to our invention, together with parts of similar blocks all in their related positions in a building wall, and

Figure 2 is an end elevation of part of a building wall showing a block according to our invention together with parts of two similar blocks in assembled relation.

Manufacturers of building blocks have for years attempted, with more or less success, to so fashion such blocks that under all conditions, and under all positions of the blocks as laid in a building wall compel any water that may, by chance, reach the interior of a constructed wall be delivered to the outer side of the wall rather than permit such water to reach the inner wall surface where much damage can be done.

Having had long experience with the manufacture and practical use of blocks in the present field we have provided a block structure to serve the purpose intended and now made known herein.

The block includes two spaced hollow rectangular portions 1 and 2, the outer side of the latter constituting in this instance the outer face in a constructed wall, and so far, of course, these portions so formed and spaced are not new in themselves.

The space between these portions is bridged by spaced bridging-walls 3 which in this instance are connected by a wall 4, said walls 3, or at least the upper one having a highest point 3' substantially midway of the spaced portions 1, 2, and sloping therefrom to their places of joining with the walls of the latter.

It is now to be noted that extending upwards from the upper wall 3 at a position between said highest point 3' and the portion 2 of the block is an integral guard portion 5 which is made to ex-

tend over and far beyond the said point 3' in the direction of the portion 1, it being noted that the upper surface of the extension 5 of this guard has a highest point at its terminal and thereby a slanting upper surface is created by which water that may reach it from above must be guided toward the portion 2, finally passing down the slope of the wall 3 to said portion 2. The under or lower surface of the named guard, it is observed, is likewise slanted downwardly toward the portion 2, and the terminal of the guard at its top may have a bead or rib 6 extending its full length as shown in Figure 1, the highest point of said bead or rib 6 lying just below a line extending across the space between the top corners of said portions 1 and 2 so that no injury can be done thereto and that normal orderly stacking of blocks can be done in storing and handling.

Moreover, due to the fact that the guard portion 5, 5', 6 is wholly below the top line of the block and within the recess of the block the blocks can be indiscriminately stacked or regardless of the position of one with respect to the other in the same way that bricks may be stacked, for example.

It is believed to be clear that since the guard 5, 5' extends some considerable distance beyond the point 3' of the upper wall 3 water that may drip thereon or reach the same by wind-driven rain through a mortar-joint directly upon the guard cannot possibly reach that part of the wall 3 that slants toward the portion 1 but, being caught must move toward the portion 2—never toward the former, and any water wind-driven up the guard's inclined surface, by chance, even if forced over the bead or rib 6 will finally follow down the lower or under wall surface of the guard then again following down the slope of the end wall portion of 3 to said portion 2. Thus, it is seen, all water must always reach the outer side only of a constructed wall.

Due to the considerable bridging of the space between the portions 1 and 2 by the guard 5, 5' narrow spaces 7, 7 are created between said guard and said positions, which through inattention of a mason might become bridged with mortar, when used, as the tops of the portions 1 and 2 are supplied with that commodity in too great bulk.

When such too great bulk is used the setting of a block thereon might tend to cause such bridging mentioned. In order to obviate this to a considerable extent, the inner lower or facing corners of the portions 1 and 2 are "relieved" at an angle as at 8 thus creating a recess the full length of the block, such recess receiving into it much of the excess mortar at those locations, minimizing

to a great extent the difficulty mentioned. Naturally the more mortar kept out of the space of the block the less chance for water to be held to maintain an undesired damp wall structure.

5. Incidentally, the guard 5, 5' besides acting in the capacity mentioned provides a convenient grasping portion for the workman, the block nicely balancing therefrom.

We claim:

10. 1. A building block including in its construction spaced portions forming the inner and outer portions of a building wall, a bridging connecting the inner sides of said spaced portions, part thereof having an upper surface sloped from a highest

15 point to a lowest point at its junction with said outer portion, and a guard erected on and integral with the wall at the said upper surface thereof between the high point of said wall and said outer portion, the terminal of said guard being

20 extended over and beyond and overhanging the said high point and projected toward the named inner portion.

25 2. A building block including in its construction spaced portions forming the inner and outer

30 portions of a building wall, a bridging connecting the inner sides of said spaced portions, part thereof having an upper surface sloped from a highest point to a lowest point at its junction with said outer portion, and a guard erected on and

35 integral with the wall at the said upper surface thereof between the high point of said wall and said outer portion, the terminal of said guard being extended over and beyond and overhanging the said high point and projected toward the

40 named inner portion, said terminal of the guard lying substantially at the same plane in which the tops of the said inner and outer portions lie.

45 3. A building block including in its construction spaced portions forming the inner and outer portions of a building wall, a bridging connecting the inner sides of said spaced portions, part thereof having an upper surface sloped from the highest point toward a lowest point at its junction with said outer portion, and a guard erected

50 on and integral with the wall at said upper surface thereof between the high point of said wall and said outer portion, the terminal of said guard being extended toward the named inner portion and overhanging the said high point,

55 50 upper surface of the guard sloping from its terminal toward the named outer portion.

55 4. A building block including in its construction spaced portions forming the inner and outer portions of a building wall, a bridging connecting the inner sides of said spaced portions, part thereof having an upper surface sloped from a highest point to a lowest point at its junction with said outer portion, and a guard erected on and

60 integral with the wall at the said upper surface thereof between the high point of said wall and said outer portion, the terminal of said guard being extended over and beyond and overhanging the said high point and projected toward the named inner portion, the said guard having an

65 upper and a lower surface, said lower surface sloping from the terminal of the guard toward the named outer portion and terminating beyond said highest point between the same and said outer portion.

5. A building block including in its construction spaced portions forming the inner and outer portions of a building wall, a bridging connecting the inner sides of said spaced portions, part thereof having an upper surface sloped from a highest point to a lowest point at its junction with said outer portion, and a guard erected on and integral with the wall at the said upper surface thereof between the high point of said wall and said outer portion, the terminal of said guard being extended over and beyond and overhanging the said high point and projected toward the named inner portion, the guard having an upper and lower surface and being spaced above the said high point of the bridging wall, and both upper and lower surfaces being inclined downwardly toward the named outer portion.

10 6. A building block including in its construction spaced portions forming the inner and outer portions of a building wall, a bridging connecting the inner sides of said spaced portions, part thereof having an upper surface sloped from the highest point to a lowest point at its junction with said outer portion, and a guard erected on and integral with the wall at said upper surface

15 thereof between the high point of said wall and said outer portion, the terminal of said guard being extended over and beyond and overhanging the said high point and projected toward the named inner portion, the upper surface of the guard sloping from its terminal toward the named outer portion, said terminal being surmounted by a rib extending upward therefrom.

20 7. A building block including in its construction spaced portions forming the inner and outer portions of a building wall, a bridging connecting the inner sides of said spaced portions, part thereof having an upper surface sloped from a highest point to a lowest point at its junction with said outer portion, and a guard erected on and integral with the wall at said upper surface

25 thereof between the high point of said wall and said outer portion, the terminal of said guard being extended over and beyond and overhanging the said high point and projected toward the named inner portion, the upper surface of the

30 guard sloping from its terminal toward the named outer portion, said terminal being surmounted by a rib extending upward therefrom.

35 8. A building block including in its construction spaced portions whose outer sides form parts of an inner and outer face of a constructed wall, a bridging wall connecting the inner walls of the

40 said spaced portions and spaced below the plane of the top surface of said block, part of said bridging wall having an upper surface sloped from a highest point thereof toward a lower point at its juncture with the outer of the two named

45 portions, and a guard erected on and integral with the wall at the upper side thereof between the high point thereof and said outer portion, said guard being wholly within the confines of the block and having a terminal projecting beyond and overhanging said high point and extending in the direction of the inner portion.

50 9. The invention according to claim 8 wherein the top surface of the extreme of said guard so projected is the highest surface of said guard.
